US00D996401S

(12) **United States Design Patent** (10) **Patent No.:** **US D996,401 S**
Han et al. (45) **Date of Patent:** **** Aug. 22, 2023**

(54) **MICROPHONE**

(71) Applicant: **Beijing Dajia Internet Information Technology Co., Ltd.**, Beijing (CN)

(72) Inventors: **Runqiang Han**, Beijing (CN); **Chen Zhang**, Beijing (CN); **Xinliang Lv**, Beijing (CN); **Xiguang Zheng**, Beijing (CN); **Qiong Yan**, Beijing (CN); **Qiao Han**, Beijing (CN)

(73) Assignee: **Beijing Dajia Internet Information Technology Co., Ltd.**, Beijing (CN)

(**) Term: **15 Years**

(21) Appl. No.: **35/515,087**

(22) Filed: **Jul. 14, 2022**

(80) **Hague Agreement Data**

Int. Filing Date: **Jul. 14, 2022**

Int. Reg. No.: **DM/223117**

Int. Reg. Date: **Jul. 14, 2022**

Int. Reg. Pub. Date: **Sep. 9, 2022**

(30) **Foreign Application Priority Data**

Jan. 26, 2022 (CN) 202230056283.7

(51) **LOC (14) Cl.** **14-01**

(52) **U.S. Cl.**

USPC **D14/225**

(57) **CLAIM**

The ornamental design for a microphone, as shown and described.

DESCRIPTION

1. Microphone

1.1 : Front

1.2 : Back

1.3 : Left

1.4 : Right

1.5 : Top

(Continued)

1.6 : Bottom

1.7 : Perspective

1 Claim, 7 Drawing Sheets
